UNITED STATES PATENT OFFICE.

GUSTAF A. WALLIN, OF FLUSHING, NEW YORK, ASSIGNOR TO A. KIMBALL COMPANY, OF NEW YORK, N. Y., A CORPORATION OF NEW YORK.

MARKING TICKET.

Application filed August 3, 1922. Serial No. 579,433.

To all whom it may concern:

Be it known that I, GUSTAF A. WALLIN, a citizen of the United States, and resident of Flushing, county of Queens, State of New York, have invented an Improvement in Marking Tickets, of which the following description, in connection with the accompanying drawing, is a specification, like characters on the drawing representing like parts.

10 This invention relates to marking tickets such as are employed for marking fabrics, garments and other articles with price, quality or other designations.

15 The object of the invention is to provide a marking ticket of this character with a coupon flap separably connected to the ticket, concealed when the ticket is applied to the article to be marked and readily removable without disturbing the functioning or external appearance of the ticket when in marking position.

20 These and other objects and features of the invention will appear more fully from the accompanying description and drawings and will be particularly pointed out in the claim.

In the drawings;

25 Fig. 1 is an obverse plan view showing a preferred form of ticket embodying the invention in marking position attached to an article such as a piece of fabric;

30 Fig. 2 is a reverse plan view of the construction shown in Fig. 1 with a portion of the ticket broken away to show the concealed coupon flap;

35 Fig. 3 is a view of one face of the entire marking ticket before it is folded and in the form furnished to the trade;

40 Fig. 4 is a similar view of the other face of the ticket;

Fig. 5 is a view in cross section taken on the line 5—5 of Fig. 1.

45 Marking tickets of this type are commonly employed when attached to fabrics, garments and other articles to carry size, style, price and other desired indicia as well as the name of the manufacturer or dealer and advertising matter. It is desirable to combine with these marking tickets a coupon or portion which may be removed therefrom when the article is sold and thus preserve a record of the sale. Such coupons may contain the duplicate of certain or all of the indicia on the marking ticket itself, or they may contain alone or in addition thereto other in-

formation of a more or less confidential nature.

This invention presents a marking ticket having such a coupon portion which may be readily removed from the main portion 60 of the marking ticket, which will be entirely concealed when the marking ticket is attached to the article to be marked and which, when removed, will not in any way interfere with the functioning of the marking ticket nor change the external appearance 65 of the marking ticket.

In the preferred form of the invention illustrated the marking ticket is shown as comprising two connected foldable main 70 flaps 1 and 2. The size and shape of these flaps will vary in accordance with the use to which the marking ticket is to be put. The line of fold 3 between these flaps is preferably formed by scoring the material 75 of which the marking ticket is made. This material is preferably a thin cardboard or thick paper such as commonly employed in marking tickets of this character.

The main flap 1 at its free end or the end 80 opposite its connection with the main flap 2 is provided with a suitable fastening device by means of which the marking ticket is secured to the goods. For this purpose an ordinary type of pointed wire staple 4 is 85 shown. The main flap 2 at its free end or the end opposite its connection with the main flap 1 is provided with apertures 5 to receive the points of the staple fastening 4.

The marking ticket is applied to the goods 90 by folding the main flaps 1 and 2 together, placing the article to be marked such as the piece of fabric 6 between the flaps passing the points of the staple fastening 4 through the fabric and through the apertures 5 and 95 bending the points of the fastening 4 back as indicated in Fig. 1.

Upon the exposed faces of the main flap 1 and 2 as indicated in Fig. 4 may be placed any desired indicia such for example as the 100 notice illustrated on the flap 2 and the number, size and price as illustrated on the flap 1.

The main flap 2 near its free end is provided with a long transverse slot 7 at a 105 point further from the free end than are the apertures 5. A covering flap 8 is connected to the free end of the slotted main flap 2 and is foldable thereupon, the line of fold being defined by the scored line 9 at 110

the point where the covering flap 8 is connected to the main flap 2. This covering flap is foldable over the fastening device projecting through the apertures 5 and is of a slightly less width than the main flap so that it may be passed through the slot 7 when the marking ticket is in position and extend between the main flaps along with the fabric 6. This covering flap therefore 10 protects and conceals the points of the pin or staple members of the fastening device 4 and prevents these points from catching on other articles or coming into contact with anyone handling the articles.

15 The coupon flap 10 is separably connected to the free end of the covering flap as by the weakened line 11 formed by partially or entirely perforating the material of the ticket. This coupon flap may be provided 20 with any desired indicia. As shown in Fig. 3 on one side it is provided with indicia similar to the main flap 1 while as shown in Fig. 4 on the other side it is provided with certain more or less confidential indicia 25 forming a record suitable to be kept by the person or concern selling the goods.

When the marking ticket is in position this coupon flap which forms with a covering flap a combined covering and coupon flap is passed through the slot 7 and lies between the main flaps 1 and 2 so that it is entirely concealed. When the sale is made 30 the salesman withdraws the combined covering and coupon flap from the slot 7 and

removes the coupon flap by tearing it off 35 along the weakened line of separation 11. The covering flap is then replaced in the slot 7 and consequently there is no change in the external appearance of the ticket, nor is the attachment of the ticket to the goods 40 or its function in any way disturbed by the removal of the coupon flap.

Having thus described my invention, what I claim as new and desire to secure by Letters Patent, is:

A marking ticket comprising two connected foldable main flaps adapted to receive between them the article to be marked, one main flap near its free end having a transverse slot and the other main flap near its free end having a fastening device provided with a portion adapted to pass through the fabric and the slotted flap and engage therewith, a covering flap connected to the free end of the slotted main flap, foldable thereupon over the fastening device and of a width enabling it to be passed through said slot and extend between the main flaps, and a coupon flap separably connected to the free end of the covering flap, normally concealed between the main flaps, and removable without disturbing the functioning or external appearance of the ticket when in marking position.

In testimony whereof, I have signed my name to this specification.

GUSTAF A. WALLIN.
